Primary Examiner — Ricky Pham

(57) **CLAIM**

The ornamental design for a threaded tumbler bottle cap, as shown and described.

DESCRIPTION

FIG. 1 is a top-left-front perspective view of a threaded tumbler bottle cap showing my design;
FIG. 2 is a bottom-right-rear perspective view thereof;
FIG. 3 is a front elevational view thereof;
FIG. 4 is a rear elevational view thereof;
FIG. 5 is a right-side elevational view thereof;
FIG. 6 is a left-side elevational view thereof;
FIG. 7 is a top plan view thereof;
FIG. 8 is a bottom plan view thereof;
FIG. 9 is a top-left-front perspective view thereof in a collapsed configuration; and,
FIG. 10 is a bottom-right-rear perspective view thereof in the collapsed configuration.
